CATHODE-RAY SIGNAL-GENERATING TUBE

Rudolf C. Hergenrother, Beechhurst, Long Island, N. Y., assignor to Baseline Corporation, a corporation of Delaware

Application August 30, 1937, Serial No. 161,568

2 Claims. (Cl. 256—153)

This invention relates to cathode-ray tube systems and, more particularly, to cathode-ray signal-generating tubes useful in television transmitting systems.

Various types of cathode-ray signal-generating tubes have heretofore been developed and, in general, they have comprised an elongated evacuated envelope including, at one end, a plurality of electrodes, conventionally referred to as an electron gun, which serve to develop, accelerate, and focus an electron beam. A photosensitive target is disposed in the opposite end of the envelope in the path of the beam. The target generally comprises a dielectric sheet, such as mica, with a continuous metallic conductive coating or signal plate on one side thereof and a photosensitive mosaic coating on the other side providing, in effect, minute condensers having the continuous metallic coating as a common electrode. Images of scenes to be transmitted are projected on the mosaic of the target and the beam is so deflected as to scan successive frames or series of parallel lines on the target. The projection of the image on the target causes photoelectron emission by the mosaic elements proportional to the light intensity at corresponding elements of the image and the electron beam, during the scanning operation, effects secondary electron emission by the mosaic elements varying in accordance with their photoelectron emission. These electrical effects are utilized to develop a correspondingly varying modulation voltage in the output circuit of the tube including the target signal plate.

Ordinarily, secondary and photoelectrons emitted from the target are collected by the electrode of the gun having the most positive potential, commonly called the second anode, and the signal plate of the target is used as an output electrode, a suitable load circuit being connected thereto. It has been found that certain advantages could be obtained by using the second anode as the output electrode but, in such an arrangement, the proximity and consequent close coupling of this electrode and the scanning elements of the tube would result in undesirable reaction effects between the signal-output voltage and the scanning fields.

It is an object of the present invention to provide an improved cathode-ray signal-generating tube characterized by simplicity of structure and reliability and efficiency in operation.

It is a further object of the invention to provide a cathode-ray tube of the character described which includes an output electrode and

circuit separate from the target structure and second anode, but not undesirably affected by other elements or circuits of the system.

In accordance with the present invention, a cathode-ray signal-generating tube comprises an electron gun for developing, accelerating, and focusing an electron beam, a second anode and a photosensitive target in the path of the beam. An output electrode is provided electrically unconnected to the second anode through any low impedance path and having an area of the same order of magnitude as that of the second anode. The output electrode is displaced from the second anode outside the path of the electron beam and in juxtaposition to the target for collecting electrons emitted by the target and there is provided means for applying operating potentials to the electrodes of the tube, the output electrode being adapted to be maintained at a potential positive relative to the second anode. With this arrangement a video-frequency modulation voltage may be developed in the output circuit which is not undesirably affected by scanning or other elements of the system.

For a better understanding of the invention, together with other and further objects thereof, reference is had to the following description taken in connection with the accompanying drawing, and its scope will be pointed out in the appended claims.

The single figure of the drawing is a schematic diagram of a complete television transmitting system including a cathode-ray signal-generating tube embodying the present invention.

Referring now more particularly to the drawing, the television transmitting system illustrated includes a conventional camera or projector 10 and a cathode-ray tube 11. This tube comprises an elongated envelope 10 including a cylindrical end portion or neck 10 and an enlarged spherical end portion 20. In the end portion 10 there is disposed a cathode 21, a control grid 22, a focusing or first anode 23, and a second anode 24, in the order named, these electrodes constituting what is conventionally referred to in the art as an electron gun. The second anode 24 preferably comprises a metallic film or coating on the inner surface of the envelope, as shown. A photosensitive target 25 is disposed in the spherical end portion 20 of the envelope. The target may be constructed in the conventional manner and include a thin sheet of dielectric, such as mica, having a metallic rear coating or signal plate and a photosensitive mosaic front surface of suitable substance, such as a silver-calcium-oxygen mixture.

or compound, thereby providing, in effect, a multitude of minute condensers having the signal plate as a common electrode. In accordance with the present invention, there is provided an additional output electrode 26, electrically unconnected to said second anode through any low impedance path, which has an area of the same order of magnitude as that of the second anode in a conventional cathode-ray signal-generating tube; that is, a substantial area sufficient to attract a large portion or substantially all of the electrons emitted by the photosensitive surface of the target. This electrode is disposed at an intermediate position in the envelope, displaced from the second anode 24, outside of the path of the beam, and in juxtaposition to the target. The electrode 26 may, similarly to the anode 24, comprise a metallic film or coating on the inner surface of the portion 20 of the envelope 18.

Suitable operating potentials are supplied to the several electrodes of the tube 11 from a voltage divider 27 connected to a suitable source, indicated as plus and minus, and grounded at an intermediate point, as shown. The output circuit includes a load resistor 28 connected at one end to the output electrode 26 and at its other end to a point on the voltage divider such that the potential applied to the output electrode is positive relative to that applied to the second anode.

There are also provided line- and frame-frequency scanning generators 12 and 13 having their output circuits connected to deflecting coils 14 and 15, respectively, of the tube 11. The output circuit of the tube including resistor 28 is connected to conventional television transmitting apparatus, indicated generally at 16 and terminating in an antenna 17.

The apparatus just described, in general, represents a conventional television transmitting system. The construction and operation of such apparatus being well known in the art, a detailed description thereof is unnecessary herein. In brief, however, in the operation of the apparatus described, images of the scene to be transmitted are projected by the camera 10 on the mosaic surface of the target 25, effecting photo-electron emission by the various mosaic elements in accordance with the light intensity at the corresponding elements of the images. Electrons are generated, accelerated, and developed into a beam by the electron gun 21-24, the beam being focused on the target 25 and causing secondary electron emission by the mosaic elements. Currents of saw-toothed wave form generated by the generators 12 and 13 are passed through the scanning coils 14 and 15, respectively, thereby producing magnetic fields which deflect the beam horizontally and vertically, causing it to scan frames or series of parallel lines on the target in the usual manner. There is thereby developed in the output circuit of the tube including the output electrode 26 a video-frequency voltage which is proportional to the variations in light and shade in the image of the scene to be transmitted. This voltage is utilized in the trans-

mitter apparatus 16 to modulate a carrier wave which is broadcast from the antenna 17 in the usual manner.

By virtue of the size of the output electrode 26, its proximity to the target 25 and the potential applied thereto, a substantial part of both the primary and secondary electrodes emitted from the target are collected by this electrode, causing a current to flow in the output circuit and a resultant voltage to be developed across the resistor 28 which are dependent upon the variations in illumination of the elements of the image projected on the mosaic. At the same time, by virtue of the location of the output electrode 26, there is a minimum interaction between the signals developed in its circuit and the periodic fluctuations impressed on the electrodes 21-24 of the electron gun and the scanning coils 14 and 15.

While there has been described what is at present considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A cathode-ray signal-generating tube comprising an electron gun for developing, accelerating, and focusing an electron beam and including a second anode, a photo-sensitive target in the path of said beam, an output electrode electrically unconnected to said second anode through any low impedance path and having an area of the same order of magnitude as that of said second anode, displaced from said second anode outside the path of said beam and in juxtaposition to said target, for collecting electrons emitted by said target, and means for applying operating potentials to the electrodes of said tube, said output electrode being adapted to be maintained at a potential positive relative to said second anode.

2. A cathode-ray signal-generating tube comprising an elongated evacuated envelope, an electron gun disposed in one end of said envelope for developing, accelerating, and focusing an electron beam and including a second anode, a photosensitive target disposed in the other end of said envelope in the path of said beam and adapted to have an image of a scene projected thereon, and an output electrode electrically unconnected to said second anode through any low impedance path and having an area of the same order of magnitude as that of said second anode, disposed at an intermediate position in said envelope displaced from said gun, outside the path of said beam, and in juxtaposition to said target, for collecting electrons emitted by said target, and means for applying operating potentials to the electrodes of said tube, said output electrode being adapted to be maintained at a potential positive relative to said second anode.

RUDOLF C. HERGENROTHER.
